UNITED STATES PATENT OFFICE.

CORINNE DOZOIS, OF OTTAWA, ONTARIO, CANADA.

GAITER.

Application filed August 12, 1924. Serial No. 731,672.

This invention relates to improvements in gaiters and like apparel, a primary object of the invention residing in the provision of a gaiter made from sheet rubber or equivalent material having resilient properties and impervious to the passage of water, especially adapted for use during the milder seasons of the year to protect the feet and ankles from rain or sleet during inclement weather, when conventional cloth gaiters or overshoes are too warm for comfortable wear.

Another object of the invention resides in the provision of a gaiter of the character set forth configurated to conform to the ankle and lower part of the limb, so that the same will remain snugly in position without the employment of appurtenances and paraphernalia for retaining the same in position.

A further object of the invention resides in the provision of a gaiter of the character stated which may be pulled over the foot and into position upon the ankle, the resilient material from which it is constructed permitting the same to stretch over the shoe, the necessity of buttoning the gaiter up the sides or opening the same in an equivalent manner being obliterated.

A still further object of the invention resides in the provision of a gaiter of the character stated having portions thereof Shirred, formed or configurated to stretch over the instep, about the ankle and about the lower part of the limb to facilitate putting the same on or removal thereof.

A still further object of the invention resides in the provision of a Shirred gaiter of the character described in which the Shirred portions serve to hold the gaiter snugly in position and conform to the contour of the instep, ankle and lower portion of the limb of the wearer.

A still further object of the invention resides in the provision of a Shirred gaiter of the character described in which the Shirred portions of the gaiter, in conjunction with the resilient material from which the gaiter is formed, will serve to accommodate itself to the insteps, ankles and lower portion of the limbs of various sizes, thus enhancing the practicability thereof from a commercial viewpoint.

A still further object of the invention resides in the provision of a gaiter of the character described, which, when not in use, may be folded into a very compact folder or

case so that the same may be carried with convenience.

With the foregoing and other objects in view, as will appear as the description proceeds, the invention consists of the novel construction as hereinafter more specifically set forth, claimed and shown in the accompanying drawings forming a part of the present application and in which:

Fig. 1 is an elevational view illustrating the application of my invention.

Fig. 2 is an enlarged fragmentary section illustrating how portions of the gaiter may be Shirred, the section being taken substantially on the plane designated by the line 2—2 on Fig. 1 in the direction of the indicating arrows.

Referring more in detail to the drawings, it will be noted that the gaiter includes a body portion 3 which is substantially tubular in formation, that is to say, the gaiter is not slit up the side in the conventional manner. Said body portion of the gaiter is preferably formed of sheet rubber or equivalent material having resilient properties and impervious to the passage of water.

To facilitate putting the gaiters on and removing the same parts thereof are Shirred, as over the instep as at 4, at the ankle as at 5, and about the upper portion of the limb as at 6, the Shirred portions being made taut by the band of rubber 7, shown in Fig. 2 which stretches about the inner face of the Shirred portion, said Shirred portion being fastened thereto in any appropriate manner such as cementing as at 8. The Shirred portions of the gaiter serve to retain the same snugly in position about the instep, ankle and limb of the wearer and also serve to retain the same in position, the necessity of appurtenances or additional paraphernalia being obliterated.

In the commercial adaptation of my invention it may be found desirable to construct certain parts of the body 3 of the gaiter from a non-resilient material, having only portions thereof resilient to accommodate the same to the conformation of the instep, ankle and limb, and for other stretching purposes as hereinbefore set forth. In view of such it is not my intention to restrict myself to the formation of a gaiter of rubber or equivalent resilient material only.

It will also be noted that I intend to employ a conventional strap 9 for retaining the

gaiter in position, although analogous or equivalent means for this purpose may be used.

While the preferred embodiment of the invention has been described, it is to be understood that minor changes in the details of construction may be resorted to within the scope of what is claimed without departing from the spirit of the invention.

10. What I claim as new is:

1. A gaiter of the character described consisting of a one piece body of resilient material, portions of said body being Shirred to render the same more stretchable than the body of the gaiter, and means for contracting said gaiter at said Shirred portions so that said gaiter will fit snugly when on the foot of the wearer.
15. 2. A gaiter including a body portion formed of water-proof material having a Shirred portion about the ankle thereof to make the same stretchable, to facilitate putting the gaiter on and removal thereof; and a piece of resilient material under said Shirred portion to contract the same, so that
20. 3. A gaiter including a body portion formed of water-proof material having a Shirred portion at the top, about the ankle, and over the instep thereof to make the same stretchable, to facilitate putting the gaiter on or removal thereof; and a piece of resilient material under each of said Shirred portions to contract the same so that the gaiter will fit snugly at the top about the limb, about the ankle and over the instep of the wearer.
25. 4. A gaiter including a body portion formed of water-proof material having a Shirred portion about the ankle thereof to make the same stretchable, to facilitate putting the gaiter on and removal thereof; and a piece of resilient material under each of said Shirred portions to contract the same so that the gaiter will fit snugly about the ankle of the wearer.

the gaiter will fit snugly about the ankle of the wearer.

3. A gaiter including a body portion formed of water-proof material having a Shirred portion over the instep thereof to make the same stretchable, to facilitate the putting on of the gaiter and the removal thereof, and a piece of resilient material under said Shirred portion to contract the same so that the gaiter will fit snugly over the instep of the wearer.

4. A gaiter including a body portion formed of water-proof material having a Shirred portion at the top, about the ankle, and over the instep thereof to make the same stretchable, to facilitate putting the gaiter on or removal thereof; and a piece of resilient material under each of said Shirred portions to contract the same so that the gaiter will fit snugly at the top about the limb, about the ankle and over the instep of the wearer.

In testimony whereof, I affix my signature.

CORINNE DOZOIS.
